United States Patent Office.

OTIS H. WEED, OF CHARLESTOWN, MASSACHUSETTS.

Letters Patent No. 74,262, dated February 11, 1868.

IMPROVED BEDSTEAD-SLAT.

The Schedule referred to in these Letters Patent and making part of the same.

TO ALL WHOM IT MAY CONCERN:

Be it known that I, OTIS H. WEED, of Charlestown, in the county of Middlesex, and State of Massachusetts, have invented certain Improvements in Bedstead-Slats, of which the following is a full, clear, and exact description, reference being had to the accompanying drawings, making part of this specification, in which—

Figure 1 is a perspective view of a bedstead-slat, having my improvement applied to the under side thereof.

Figure 2 is a vertical section through the centre of the same.

Figure 3 represents the position of the parts when the slat is bent down at the centre.

Figure 4 is a side elevation of the spring which I apply to the under side of the slat.

Bedstead-slats have been provided on their under surfaces with long wire springs, coiled, and secured at each end to the slat, and so arranged as to support it at the centre, for the purpose of preventing it from becoming permanently bent down by continued use, as described in the patent of N. J. Willis for bed-bottom, dated January 22, 1867. Two wire springs have also been applied to a slat, one end only of each spring being secured thereto, the opposite end sliding beneath a staple or guide. These springs, however, being made of wire, do not possess the necessary degree of strength and elasticity to effect the desired object, and are also liable to become "set" by the bending of the slat, thus rendering them useless. My invention has for its object to overcome these difficulties, and consists in the application, to the under side of a bedstead-slat, of a spring of flat tempered steel, secured permanently thereto, the spring being so formed and arranged that it will bear against the central portion of the slat, thus acting as a lifter to retain it in its original form, and effectually preventing it from becoming permanently bent down at the centre.

To enable others skilled in the art to understand and use my invention, I will proceed to describe the manner in which I have carried it out.

In the said drawings, A represents a wooden bedstead-slat, to the under surface of which is secured a spring, B, of flat tempered steel. This spring, which is made in the form represented in fig. 4, is permanently secured, at each end, to the slat A, by means of screws or rivets *a*; and, when secured in place, its central curved portion, *b*, will exert a pressure on the centre of the slat sufficient to retain it in its original curved form, and prevent it from sagging and becoming permanently bent down at the centre from constant use, as is frequently the case where wire springs are employed.

A spring constructed as above described, of flat tempered steel, possesses a great degree of strength and elasticity, and is not liable to become "set," thus presenting great advantages over a spring made of wire, and particularly adapting it for the purpose to which it is applied, while by its use I am enabled to employ very light slats, the spring serving to stiffen the slat at the centre; and, if the latter is bent down by any unusual weight, as seen in fig. 3, the spring will be drawn out, so as to conform at all points to the curvature of the slat when (being secured at each end at *a*) it acts as a strap or brace to prevent the slat from breaking or being bent down too far.

Claim.

What I claim as my invention, and desire to secure by Letters Patent, is—

The combination of the spring B, of flat tempered steel, with the slat A, when the spring is constructed with a double curvature, the centre resting against the slat, as shown, and arranged so as to operate substantially as and for the purpose described.
